COMBINED CLOCK AND RACK

Don V. Tara, Miami Beach, Fla.

Application May 29, 1958, Serial No. 51,130

Term of patent 3½ years

(Cl. D42—7)

Fig. 1 is a top plan view of a combined clock and rack, showing my new design; Fig. 2 is a front elevational view; Fig. 3 is a bottom view; Fig. 4 is a side elevational view; and Fig. 5 is a rear elevational view thereof.

I claim:

The ornamental design for a combined clock and rack, as shown.
